WASHING APPARATUS
Louis A. Derwin, 4508 Cross St.,
Downers Grove, Ill. 60515
Filed Sept. 12, 1966, Ser. No. 578,662
7 Claims. (Cl. 15—3)

This invention is directed to a washing device and more specifically concerns an apparatus for washing automobiles though not specifically restricted thereto.

In car wash stands the principal difficulty is the lack of consistent labor supply. Those stations which feature self-service employ a high stream jet of water with a cleaning solvent such as any well known detergent and rely upon the impingement action of the water to scour off the dirt. At best this has been found to be a makeshift proposition.

A general object of the present invention is to provide novel apparatus which includes a projectile saturable with a cleaning solution and which is adapted to be thrown with such velocity at the object to be washed as to cause the projectile to deform against the surface to be washed and to slide therealong in an action simulating hand washing to physically remove the dirt.

A more specific object is to provide a novel system for washing objects which includes a support for such object within an enclosure into which project one or more guns trained upon the object to be washed, these guns directing sponges or the like saturated with water and detergent against the object, the sponges sliding off the object into a collection pit from whence they are recirculated through appropriate cleaning and squeezing or kneading apparatus into the said guns.

These and other objects and advantages inherent in and encompassed by the invention will become more readily apparent from the specification and the drawings, wherein:

FIGURE 1 is a vertical sectional view of a building and car washing apparatus in accordance with this invention, and

FIGURE 2 is a sectional view taken essentially on line 2—2 of FIGURE 1 of the slinger mechanism.

The invention is shown in connection with a car wash station 1 and includes an enclosure generally designated 2 which comprises an appropriate building having a roof 3 and four sides 4 (only three of which are shown), two of the opposite sides each including a door 5 for ingress and egress of the article to be washed such as the car 6. These doors would, of course, be closed during the washing operation.

The bottom of the enclosure may comprise a turntable 7 having a top plate or floor structure 8 of grille-work form to provide vertical apertures 9 therethrough communicating with a pit or sump 10 which may be of trough or annular shape having vertical sides 11 defining an opening 12 into which fits the aforementioned floor structure 8, the latter being carried at its center from a vertical rotatable support or shaft 13 which may be combined with the shaft of a hermetically sealed appropriately geared down power unit 15 such as an electric motor which may be suitably anchored via its housing 16 to the bottom wall 17 of the sump.

The automobile 6 is driven into the enclosure through one of the doors 5 upon guide rails 18 which may be secured upon the floor structure. Thereupon the doors are closed and the operator or the customer proceeds to wash the vehicle by suitably starting the washing apparatus generally designated 25. The specific starting and stopping means is of no consequence in the present invention, but may consist of switch controlled suitable electrical wiring to the various valves and motors hereinafter described.

2

Upon initiating the unit, the operator preferably manually controls the gun or nozzle 26 by grasping the hand-hold 27 on the barrel 28 of the gun and aiming it onto the area of the car intended to be washed.

5 A stream of either synthetic or natural sponges 30 issue at high velocity from the barrel, these sponges being saturated or permeated with a solution of water and detergent, said sponges being of a consistency somewhat that of natural sponge. These sponges or projectiles 30 (which could be of disposable paper or inexpensive polyurethane or other plastic material and therefore expendable upon single use) strike the surface to be washed, deform to the contour of the surface and because of the lubricant (washing vehicle) therein slide along the 10 surface to be washed with a wiping action whereby cleaning such surface. If reusable sponges are used, these drop into the sump through the grille flooring and float in the liquid 32 in the sump to an elevator 33, the liquid being circulated toward the elevator by a pump 34 which has an inlet line 35 connected through a vertical wall 11 of the 15 sump behind the elevator conveyor 33 and has an exhaust line 37 connected through the bottom 17 of the sump in an area diametrically opposite the inlet.

The conveyor may be an endless chain apron type 20 having a front pick-up or advance run 39 and a return or back run 40, the apron being trained at its lower end upon a sprocket assembly 42 adjacent to the bottom of the sump from said suitable structure (not shown) and extending diagonally upwardly above the sump over and 25 beyond the upper edge 43 of side wall 11 of the sump and at its upper discharge end 44, the conveyor apron is trained about a powered sprocket and shaft assembly 45 which is suitably supported.

The apron includes a plurality of scoops 46 which 30 extend transversely on the apron and dip through the solution 32 and carry the dirt laden sponges 30 over the discharge end 44 into a hopper 47 which is supported therebelow. The hopper discharges gravitationally through a bottom opening 48 into the intake nip 50 35 of a pair of squeeze rollers 51, 51 which are power driven and each comprising a shaft 52 and a body 53 of metal, or preferably elastomer material, such as synthetic or natural rubber. These rollers rotate at such speed as to 40 propel the sponges, squeezed almost dry, through a washing chamber 54 which may be below the floor 55 from which depend spray nozzles 56 which are connected to a suitable source of water or cleaning fluid. The nozzles are 45 preferably oriented to direct a fluid stream toward the discharge end or side 57 of the chamber 54 to augment the propulsion of the sponges along the floor 55 of chamber 54 to the intake nip of a pair of second squeeze rollers 58, 58 each of which may be powered and are 50 in essence of the same construction as rollers 51 and are mounted upon suitable support structure. The wall 55 may slope toward rollers 58. These rollers 58 rotate 55 in directions as shown and have a discharge area 59 facing the return run 60 of an elevating conveyor 61 which in essence is of the same construction as conveyor 33. The conveyor 61 has a bottom loop 63 which is 60 trained about a sprocket and shaft assembly within a hopper 64 which is below rollers 58, the conveyor 61 having its lifting apron run 65 carrying the sponges in scoops 66 upwardly through an opening 67 in the floor 55 and over an idler sprocket assembly 68 and then 65 diagonally upwardly over a powered sprocket assembly 70 at its discharge end 71 whereat the sponges are dumped into a hopper 72 which has a discharge funnel 73 guiding the descent of the sponges onto a slinger or thrower or impeller 75 which in the present instance is shown as a disk 76 connected to a vertical shaft 77 which is driven by a motor 78 located below and mounted from the bottom plate 79 of the housing 80.

The sponges may be saturated from above by sprays 81 which project into the housing 80 from its top wall 82 and hold the sponges against the top side 83 of the plate 76 between the radial vanes or blades 84 projecting upwardly from and connected to plate 76.

The sponges drop into the center eye 85 of the slinger and by centrifugal action are impelled radially outwardly toward the peripheral wall 86 of the housing, said wall 86 confining the sponges on the plate until they exit from the outlets 87 defined between the blades adjacent to the outer periphery of the disk upon said outlets aligning with the discharge opening 90 in the housing 80.

The speed of rotation of the slinger and the distance of travel of the sector of the disk carrying the sponges is so proportioned as to normally cause the sponges to sling out of the housing in the area of the outlet 90 which is connected to a duct 91, which has a flexible tube portion 92 connected to said barrel 26 whereby the latter may be oscillated to be directed against various areas of the car to be cleaned.

It will be noted that the barrel with the flexible tubing projects through an opening 93 in a side wall of the enclosure.

If expendable cleaning elements 30 are used, the sump may be made large enough to accommodate a day's or week's supply and the recirculating conveyor and sponge cleaning system would be eliminated. Instead the hopper 72 may be a magazine or supplied with a predetermined quantity or metered amount of pellets in accordance with a specified charge from the customer and the system may be of the "coin operated" type.

The car may be automatically rotated on the turntable or may be actuated at the option of the operator.

I claim:

1. An article cleaning apparatus comprising a deformable projectile element, means for coating said projectile element with a cleaning medium, and means for casting said projectile element against the article to be cleaned with a force sufficient to cause said element to deform against the object and slide along the same with a wiping action, and a turntable having a perforated floor for supporting the article to be washed, a sump beneath said turntable for collecting fluid and the cleaning elements thrown against the article, said elements adapted to drop through the perforated floor, means for collecting the cleaning elements from said sump and returning the same to said casting means and including means for wringing

said elements and cleaning the same while in transit to said casting means.

2. The invention according to claim 1 and said means for wringing said elements including a cleaning chamber and cooperative roller means adapted to squeeze the said elements therebetween and operative to propel the elements through said chamber.

3. The invention according to claim 2 and further means in said chamber for augmenting movement of said cleaning elements through said chamber and including a jet spray of cleaning liquid oriented to impinge against said elements in a direction exiting said elements from said chamber.

4. A vehicle cleaning apparatus comprising means for supporting the vehicle, a nozzle, means for relatively movably positioning the nozzle and vehicle, cleaning elements adapted to be discharged from the nozzle against the vehicle to be washed, means for collecting and re-cycling said elements and including means for wringing, cleaning and reconditioning the surface of each element with a cleaning solution, and centrifugal pump means for propelling the cleaned and reconditioned elements through said nozzle.

5. The invention according to claim 4 and said pump means comprising a plurality of vane members, and means for disposing the reconditioned elements between said vane members.

6. The invention according to claim 4 and means for depositing the cleaning solution onto the surfaces of said elements at said pump means.

7. The invention according to claim 4 and said pump means comprising a vane member, a housing enclosing said vane member and having a tangential outlet, and means for depositing the reconditioned elements into the housing remote from said outlet.
